Patented Aug. 8, 1916.

UNITED STATES PATENT OFFICE.

PETER PEARSON, OF MENOMINEE, MICHIGAN.

VENTILATOR.

1,194,314.

Specification of Letters Patent.

Patented Aug. 8, 1916.

Application filed July 22, 1914. Serial No. 852,409.

To all whom it may concern:

Be it known that I, PETER PEARSON, a citizen of the United States, residing at Menominee, in the county of Menominee and State of Michigan, have invented a new and useful Ventilator, of which the following is a specification.

This invention relates to improvements in ventilators and more particularly to that 10 class intended for use with railroad cars.

An object of the present invention is to provide a car ventilator which is adapted to exhaust the air from a car without likelihood of rain or snow being driven in 15 through the air exit, at the same time accomplishing the foregoing without rendering the device unsightly or awkward in appearance, which would prohibit its use.

A further object is to provide a ventilator 20 of such construction that it will be extremely rigid and thus able to withstand hard usage to which it will be necessarily exposed.

With the foregoing and other objects in 25 view which will appear as the description proceeds, the invention resides in the combination and arrangement of parts and in the details of construction hereinafter described and claimed, it being understood 30 that changes in the precise embodiment of the invention herein disclosed, can be made within the scope of what is claimed, without departing from the spirit of the invention.

In the drawings accompanying this specification and forming a part thereof, the preferred embodiment of my invention is illustrated.

In said drawings:—Figure 1 is a sectional view of the ventilator, illustrating the same 40 as being secured to a roof. Fig. 2 is a cross sectional view taken on the line 2—2 of Fig. 1. Fig. 3 is a cross sectional view taken on the line 3—3 of Fig. 1.

Referring to the drawings in which similar reference numerals designate corresponding parts throughout the several views, a car roof 4 is provided with the aperture 5 therein and to the side walls of which are secured the brackets 6 whereby the 50 ventilator casing or housing 7 is rigidly secured to and extends through the car roof.

The housing 7 is substantially cylindrical in contour and includes a partition 8 intermediate its ends, thus dividing the housing 55 into an upper driving fan compartment 9 and a lower ventilating fan compartment

10, the same being mutually independent and noncommunicating as will be apparent from Fig. 1. The driving fan compartment 9 is closed at its upper extremity by the cover 11 while as the side walls of the said compartment are provided with the diametrically opposed lipped openings 12 whose diametric center line extends substantially parallel to the longitudinal axis of 60 the car and therefore in alignment with the direction of travel thereof.

A shaft 13 extends axially of the housing, projecting through an aperture 14 within the partition and supported at its upper 65 extremity by the bearing 15 and at its lower extremity by the vertical bearing 16. The upper bearing end includes a block 17 rigidly secured to the center of the cover 11 and through which block extends the bolt 18 70 which is held in adjusted position by means of the lock nut 19. The lower extremity of the bolt is pointed as at 20 and coacts with a conical recess 21 within the shaft so as to effect a bearing therebetween. The lower 75 bearing 16 includes a horizontally disposed strip 22 extending between the walls of the housing and supporting the weight of the shaft and the various members disposed thereon. The bearing strip is provided with 80 a recess 23 therein in which the pointed extremity 24 of the shaft seats, and thus effects 85 a step bearing therewith.

A driving fan 25 is rigidly mounted upon and is adapted to rotate the shaft 13, being 90 driven by the air which is forcibly projected through the openings 12 in the side walls of the housing. The driving fan is of the horizontal type and includes a plurality of substantially V-shaped blades 26 disposed at 95 one side and radially of the shaft as disclosed in Fig. 2. As the air passes through the openings 12—12 due to the forward travel of the car, the air coming into contact with the blades of the fan forcibly rotates 100 the latter and thus actuates the shaft. An exhausting or ventilating fan 27 is rigidly secured to the shaft, is of the propeller type and is adapted to forcibly withdraw the air from the lower portions of the housing and 105 therefore from the compartment with which the housing communicates.

The lower extremity of the housing is open to thus define an inlet 28, whereas, the upper extremity of the driving fan compartment is provided with a plurality of outlet 110 apertures 29 arranged as a single horizontal

row, through which the air from the housing makes its exit. A hood or cowl 30 is rigidly secured to the housing at its upper extremity in alinement with the partition 8 so that the pressure exerted upon the housing due to the securement of cowl will be taken up and borne by the partition in question. The cowl projects downwardly and outwardly and houses and protects the outlet openings 29, thus preventing snow and cinders from being driven into the fan compartment which would prevent the proper operation of the exhausting fan and also be liable to make their way into the interior of the car. The number of ventilators installed upon each car may be varied as desired and consistent with the proper ventilation thereof.

Having thus fully described my invention, what I claim is:—

The combination with a structure to be ventilated, said structure having an opening in the top thereof, of a housing having an open end seated within the opening in said structure, said housing extending above the structure, an imperforate partition dividing the housing into a lower and upper compartment, said compartments being out of

communication, there being outlet openings in the upper portion of the lower compartment and diametrically opposed front and back openings in the wall of the upper compartment, a central shaft extending longitudinally within the housing, an exhaust fan revoluble with the shaft and arranged within the lower compartment, a driving fan secured to the shaft and located in the upper compartment in position to be actuated by a current of air flowing through the said compartment by way of the diametrically opposed openings therein, the blades of said fan being V-shaped in transverse section and separated at their inner ends, and an endless hood extending around the casing above the openings in the wall of the lower compartment, said hood extending downwardly across the openings and being substantially frusto-conical.

In testimony that I claim the foregoing as my own, I have hereto affixed my signature in the presence of two witnesses.

PETER PEARSON.
